PRODUCTION OF KETONES

Gennady M. Kosolapoff, Auburn, Ala., assignor
to Monsanto Chemical Company, St. Louis,
Mo., a corporation of Delaware

No Drawing. Application December 14, 1950,
Serial No. 200,879

5 Claims. (Cl. 260—592)

1

This invention relates to the production of aromatic ketones by a novel method and more particularly to certain ketones not obtainable by prior methods.

A present object is to provide a method to obtain acetophenone derivatives useful in perfumery. In the case of the higher molecular weight compounds, the products may also be used as plasticizers. An object is also to prepare diacetyl derivatives of aryl compounds. Such products have not been generally obtainable by prior art methods such as the Friedel-Crafts reaction.

Another object of the invention is to prepare acetophenones which may be transformed into various vinyl compounds. Other objects will be apparent from the following description.

Acetophenone and its derivatives have been prepared by a number of methods, but the prior methods have been characterized by high costs, because of the numerous steps involved and the expensive catalysts necessary. Acetophenones have also been made by the Friedel-Crafts reaction, but the present invention dispenses with the use of the more expensive acid anhydrides and halides heretofore necessary; instead, the cheaper acids may be used directly to manufacture the mono-acetyl derivatives. In addition the poly-acetylated aromatic compounds, not obtainable by prior art methods, may now also be prepared.

I have now found that aromatic ketones may be prepared by reaction of carboxylic acids with alkyl substituted aromatic compounds in the presence of phosphorus pentoxide. The alkyl radical may have from 1 to 18 carbon atoms and may be primary, secondary or tertiary in character. There may be one or more alkyl groups up to three per aromatic ring.

Examples of suitable alkyl substituted aromatic compounds are the following: toluene, ortho-, meta-, or paraxylene, mesitylene, mono-, di- or triethylbenzene, n-propylbenzene, cumene, paracymene, n-butylbenzene, secondary butylbenzene, tertiary butylbenzene, cyclohexylbenzene, octylbenzene, dodecylbenzene, octadecylbenzene.

Suitable carboxylic acids may be any of the monobasic aliphatic carboxylic acids having more than 2 carbon atoms in the molecule, such, for example, as acetic, propionic, butyric, valeric, caproic, heptylic, caprylic, pelargonic, capric, lauric, myristic, palmitic, stearic, oleic, arachidic, behenic, lignoceric, cerotic, etc.

The general reaction appears to proceed as indicated by the equation:

2

where m and n are integers having a value of from 1 to 3, R is an alkyl group and R' is also an alkyl group having from 1 to 18 carbon atoms.

When there is only one alkyl substituent in the ring of the aromatic compound, the carbonyl substituent generally enters the ring para to the alkyl group. When there are two alkyl substituents in the ring in para-position the carbonyl substituent enters at the 2- or 5-position. When there is substitution of two carbonyl substituents the substitution occurs mainly at the 2- and 5-position. Where there is substitution of more than one carbonyl substituent, a mixture of mono- and di-carbonyl substituted aromatic compounds is produced. This mixture can be resolved usually by careful fractional distillation.

The invention is best carried out by mixing the ingredients in the proportions required for the production of the desired compound. The mixture is heated to accelerate the reaction. Conveniently it may be heated to the refluxing temperature of the acid-hydrocarbon mixture. Refluxing may take place at ordinary atmospheric pressure. However, temperatures other than that provided for by atmosphere temperature refluxing may also be employed. The reactivity of the alkyl aromatic body will vary directly with the number of alkyl substituents present. Thus, a dialkyl substituted aromatic compound is more reactive than a mono-alkyl compound and a trialkyl compound is more active than the dialkyl derivative. Symmetrically disposed alkyl substituents on the benzene ring are more reactive than unsymmetrical ones. Accordingly, the temperature to which the reaction mixture is heated should be varied, depending upon the type of compound undergoing reaction and the time during which reaction is to be completed. In general, lower temperatures require longer times of reaction.

Since the P_2O_5 is required to be present in the reaction, it is desirable that it be intimately dispersed therein. Fortunately, P_2O_5 is obtainable as a finely divided solid which, when dry, is readily dispersed by efficient stirring. However, water is liberated during the reaction or may be present in small quantities in the reactants which will combine with the P_2O_5 to form metaphosphoric acid. The phosphoric acid so formed is a sticky or gummy substance which is difficult to disperse itself and when present in substantial amounts will tend to occlude dry P_2O_5 , making it more or less unavailable to the reactants. For this reason I prefer to have present a further dispersing agent which should be an inert material. For this purpose I may employ any inert solid or liquid. Solid dispersing agents which are useful for the present purpose are finely divided forms of silica, such as diatomaceous earth, finely ground quartz, finely di-

vided silica gel, silica aerogel, etc. The amount of silica employed will depend upon the amount of water liberated and the amount of P_2O_5 present. In general, it is desired to utilize only sufficient P_2O_5 necessary to combine with the water liberated by the reaction so as to form metaphosphoric acid therewith. However, it is not always possible to completely react all of the P_2O_5 employed by reason of mechanical difficulties in dispersing this substance. However, by employing a finely divided inert material in conjunction with the P_2O_5 a better economy of P_2O_5 is realized.

My invention is further illustrated by means of the following examples:

Example 1

Meta-xylene (106 g., 1.0 mole) and glacial acetic acid (60 g., 1.0 mole) were mixed in a flask equipped with a stirrer and a reflux condenser protected by a calcium chloride tube. With the stirrer in operation, 3 g. of Celite filter aid (a diatomaceous form of practically pure silica) was added to the mixture, followed by 71 g. phosphorus pentoxide (0.5 mole). Vigorous stirring and refluxing for two hours was sufficient for reaction. It was noted that the mixture first coagulated temporarily to a viscous mass and then began to liquefy and remain quite fluid because of the presence of the dispersing filter aid. On cooling, the organic layer was decanted from the semi-solid inorganic matter, which was extracted to obtain an increment of the organic product. Distillation of the final product, under reduced pressure, gave 52 g. of 2,4-dimethyl acetophenone as a colorless liquid, B. P. 120-5°/20 mm. and 10 g. of dimethyl diacetylbenzene as a rapidly crystallizing oil, B. P. 100-150°/5 mm.

Example 2

The preceding example was repeated using a 30-minute reaction period to yield 53 g. dimethyl acetophenone and 12 g. dimethyl diacetylbenzene.

Example 3

Repetition of meta-xylene run. 53 g. (0.5 mole) of meta-xylene, 60 g. (1 mole) of acetic acid and 71 g. (0.5 mole) of phosphorus pentoxide were charged to obtain a yield of 20 g. dimethyl acetophenone, 30 g. dimethyl diacetylbenzene and 20 g. of a dark, semi-crystalline residue.

The dimethyl acetophenone fractions were combined and redistilled to yield pure 2,4-dimethyl acetophenone, B. P. 117-18°, $n_D^{25}=1.5315$. The structure was confirmed by hypochlorite oxidation in 95% yield to 2,4-dimethyl benzoic acid, M. P. 125.2° from hot water.

The dimethyl diacetylbenzene fractions were combined and recrystallized from alcohol to yield the compound as colorless needles, M. P. 123.5-124°.

Example 4

The preceding procedure was applied with toluene (92 g., 1.0 mole) glacial acetic acid (60 g., 1.0 mole) and phosphorus pentoxide (71 g., 0.5 mole) with 3 g. of Celite. Reaction for two hours yielded methyl acetophenone, B. P. 115-20°/20 mm.

Example 5

Cyclohexylbenzene.—A run analogous to the toluene run gave as a high boiling oil, cyclohexyl acetophenone, B. P. 150-60°/10 mm.

Example 6

Tert.-butylbenzene.—A run, as given above, gave tert.-butyl acetophenone, B. P. 150-60°/20 mm.

Example 7

Mesitylene.—100 g. of mesitylene, 120 g. of glacial acetic acid, 71 g. of phosphorus pentoxide and 5 g. of Celite gave, after a 90-minute reaction, 90 g. of acetomesitylene, B. P. 100-2°/ca. 4 mm. for an 82.5% yield.

Example 8

Propionic acid.—100 g. of meta-xylene, 25 g. of propionic acid and 25 g. of P_2O_5 were mixed in the presence of 3 g. of Celite using stirring at reflux temperature for one hour. After recovery of unused xylene, this reaction gave 19 g. of 2,4-dimethyl propiophenone, B. P. 115-20°/16 mm. and 15 g. of higher boiling dipropionyl derivatives of the phosphoric acid.

Example 9

Stearic acid.—100 g. of meta-xylene, 20 g. of stearic acid, 10 g. of P_2O_5 and 3 g. of Celite were stirred at reflux for 2½ hours. The products were, after distillation to remove excess xylene and stearic acid, 3 g. of 2,4-dimethyl stearophenone, B. P. 250-70°/15 mm., M. P. 40°. A further portion of the reaction product consisted of higher boiling point derivatives.

This application is a continuation-in-part of my application Serial No. 679,559, filed June 26, 1946, now abandoned.

What I claim is:

1. The process which comprises reacting an alkyl substituted aromatic compound, said aromatic compound containing not in excess of 3 alkyl substituents with an aliphatic monocarboxylic acid in the presence of phosphorus pentoxide.
2. The process which comprises reacting toluene with an aliphatic monocarboxylic acid in the presence of phosphorus pentoxide.
3. The process which comprises reacting xylene with an aliphatic monocarboxylic acid in the presence of phosphorus pentoxide.
4. The process defined in claim 2, in which the aliphatic monocarboxylic acid is acetic acid.
5. The process defined in claim 3, in which the aliphatic monocarboxylic acid is acetic acid.

GENNADY M. KOSOLAPOFF.
